CONTROL CONSOLE FOR DEBURRING APPARATUS

Robert L. Paden, Rochester, N.Y., assignor to El-Chem
Machinery, Inc., Rochester, N.Y., a corporation of New
York

Filed Sept. 25, 1968, Ser. No. 13,696

Term of patent 14 years

Int. Cl. D15—05

U.S. Cl. D55—1

FIG. 1

FIG. 2

FIG. 3

FIG. 4

FIG. 5

FIG. 6

FIG. 1 is a perspective view of a control console for deburring apparatus, showing my new design;

FIG. 2 is a front elevation thereof;

FIG. 3 is an end elevation showing the left hand end thereof;

FIG. 4 is a similar view of the right hand end thereof;

FIG. 5 is a rear elevation thereof; and

FIG. 6 is a plan thereof.

I claim:

The ornamental design for a control console for deburring apparatus, substantially as shown.
